UNITED STATES PATENT OFFICE.

JOHN P. OLSON AND MOGENS C. CHRISTENSEN, OF TACOMA, WASHINGTON.

SAW-SETTING TOOL.

No. 872,445.

Specification of Letters Patent.

Patented Dec. 8, 1907.

Application filed December 17, 1903, Serial No. 185,541.

To all whom it may concern:

Be it known that we, JOHN P. OLSON and MOGENS C. CHRISTENSEN, citizens of the United States of America, and residents of Tacoma, in the county of Pierce and State of Washington, have invented certain new and useful Improvements in Saw-Setting Tools, of which the following is a specification.

Our invention relates to tools for gaging and correcting the set of saw teeth and has for its object to provide a single tool with which this may be done so that time and labor in setting saw teeth may be saved. We attain this object by the device illustrated in the accompanying drawing, in which

Figure 1 is a side view of our device gaging a tooth imperfectly set, Fig. 2 is a similar view showing our device applied to the side of the tooth so as to act as a hammer set, Fig. 3 is a view similar to Fig. 1 showing our device gaging a perfectly set tooth, and Fig. 4 is a front view of our device.

Similar letters of reference refer to similar parts throughout the several views.

It has been customary, in setting saw teeth, to have two tools; the spider gage, for indicating the set of the tooth; and the hammer set, for bending the tooth to the correct set. In order to operate with these tools it was necessary to first gage the tooth, then lay down the spider gage, pick up the hammer set, strike a blow with the hammer, then lay down the hammer set, pick up the spider gage, test the set of the tooth, and if the set was then not correct the same proceeding would have to be repeated.

With our invention the two tools are replaced by a single one so that the successive laying down of one tool and picking up of another tool is eliminated and the single tool is simply moved so that different portions thereof are brought into successive use.

Our invention consists of a heavy iron casting "A" provided with slight depressions "B" in the sides thereof which are placed herein so as to fit the grip of the hand. The lower surface "C" of the casting is inclined and is intended for the little finger of the hand to lie under and thus to support the casting "A" more securely in the hand. The working side of the casting "A" is divided into two main surfaces set at an angle to each

other as shown in the drawing. The upper surface "D" thereof is beveled off, as at "E", along its upper edge and is adapted to act as a hammer set, while the lower surface "F" is provided with three projections "G" thereon which terminate in one plane (different from the plane of the surface "D") and which act in conjunction with the adjustable projection, on the upper part of the tool, to form a spider gage. This adjustable projection consists of the lug "H", formed in one corner of the upper side of the casting "A", and the screw "I" passing through the lug "H" practically at right angles to the plane of the projections "G". The lock nut "J" keeps the screw "I" at the proper adjustment. The saw body is indicated on the drawing at "K" and the saw tooth at "L".

The operation of our device is as follows:— Referring to Fig. 1 the projections "G" are placed against the body "K" of the saw in such a position that the end of the screw "I" comes opposite the point of the teeth "L" to be tested. If, as in this case, there is play between the screw "I" and the saw tooth "L", the tooth needs to be set further out; or, if the tooth "L" comes in contact with the screw "I" and there is play between either of the upper projections "G" and the saw body "K", then the tooth is set too far out; but, if there is no play then the tooth is correctly set, as in Fig. 3.

If the tooth needs setting the casting "A" is slightly raised and tipped forward so that the surface "E" comes against the saw "K" and the tooth "L" in such a manner that the shoulder of the tooth comes very slightly above the lower line of the bevel edge "D". Then the tooth "L" is struck a blow with a hammer so as to bend its end to give the required set. Then the casting "A" is lowered again and tipped back to its original level and the screw "I" is brought to the tooth "L" and the set is tested.

It will be noted that in the shape of the working side of the casting "A", it is essential that the plane of the surface "K" be at an angle with the plane on which the outer surfaces of the projections "G" lie. The reason for this is clearly indicated in Figs. 1 and 2; in gaging the tooth the surface "E" is withdrawn out of the way, and in setting the tooth the surface "F" and the projections "G" are withdrawn.

Having now described our invention, what we claim and desire to secure by Letters Patent is:—

A saw-set and gage consisting of a heavy body having a hammer-set anvil and a spider-gage in two planes which together form a single continuous working face and which are set at an obtuse angle to each other.

Signed at Tacoma this 19th day of November 1903.

JOHN P. OLSON.
MOGENS C. CHRISTENSEN.
